UNITED STATES PATENT OFFICE

2,470,683

VERTICAL SEMICYLINDRICAL BURNER

James L. Breese and Bruce Hayter, Santa Fe, N. Mex., assignors, by mesne assignments, to Breese Burners, Inc., Santa Fe, N. Mex., a corporation of Delaware

Application September 15, 1944, Serial No. 554,264

3 Claims. (Cl. 158—91)

1

The invention relates to an improvement in liquid fuel burners and has for one purpose to provide a vaporizing burner in which a liquid fuel is vaporized in a mixing chamber, the vaporized fuel being mixed with primary air to produce an initial mixture, the initial mixture being mixed with secondary air to form a final and fully combustible mixture.

Another purpose is to provide improved means for vaporizing liquid fuel in a pot type burner.

Another purpose is to provide a structure in which the liquid fuel, during vaporization, is subjected to the maximum heat of combustion taking place in or near the burner.

Another purpose is to provide a liquid fuel burner with a generally upright vaporizing plate or member.

Other purposes will appear from time to time in the course of the specification and claims.

We illustrate the invention more or less diagrammatically in the accompanying drawings wherein:

Figure 1 is a vertical section;

Figure 2 is a section on the line 2—2 of Figure 1; and

Figure 3 is a section on the line 3—3 of Figure 2. Like parts are indicated by like symbols throughout the specification and drawings.

Referring to the drawings, 1 generally indicates any suitable heater or heat exchange member, such as a stove, furnace or oven, the details of which do not of themselves form part of the present invention. It is shown as having a bottom wall 2 provided with an aperture 3. 4 illustrates a liquid fuel vaporizing wall. It is shown as generally plane and generally vertical. However, its contour and angle may be substantially varied. 5 indicates a generally semi-cylindrical wall which, with the vaporizing wall 4 constitutes a burner pot. 6 is a top wall or ring for the pot having an inner arcuate edge 8, for convenience formed about the center 9 in the plane of the vaporizing wall 4. It thus defines an aperture 7 aligned with the aperture 3 of the wall 2, through which the flame and the products of combustion may pass from the interior of the pot to the interior of the heater 1. We illustrate the wall 5 as having a flange 10. It may be secured in any suitable fashion to a base plate 11 which in turn may be secured by any suitable securing means 12 to the wall 2. The semi-cylindrical pot wall 5 is shown as having a plurality of primary air inlet apertures 18 located at various distances from the end of the pot. Any suitable means for admitting second-

2

ary air may be employed. We illustrate for example a single row of secondary air inlets 19. They are shown as larger and more closely spaced than the primary air inlets 18, and their axes may converge on the aperture 7 of the ring or plate 6. 20 is any suitable bottom plate or closure for the pot. Liquid fuel may be delivered, for vaporization, to the vaporizing wall 4 by any suitable means. We illustrate for example a fuel tank 21 from which extends a duct or supply pipe 22 having an end 23 which extends through the wall 4. It may be advantageous to incline the wall 4 slightly from the vertical, so that the liquid fuel delivered to the face of the wall will flow downwardly directly across the face of the wall and will be subjected to the heat of combustion taking place within the mixing chamber or pot. 24 indicates any suitable valve means for controlling the rate of flow of the liquid fuel to the wall 4. It may be controlled for example by the handle 25. It will be realized, however, that any suitable means, manual or automatic, may be employed for varying and controlling the rate of flow of the liquid fuel.

25 We may employ any suitable means for reducing or cutting off the flow from the tank 21, in the event that an excess supply of liquid fuel is delivered to the interior of the pot. We may employ for example the discharge duct 30 which delivers liquid fuel to any suitable trip bucket 31 adapted through the linkage generally indicated at 32, to move the cut off valve 33 to the closed position. If the burner goes out the flow of liquid fuel will shortly trip the bucket 31 and terminate any further fuel delivery. If, for any reason, more liquid fuel is delivered than the burner will consume, the same result is obtained, and a further flow of liquid fuel is cut off.

Assuming that the burner operates normally, 40 at a predetermined rate of liquid fuel flow, the liquid flowing across the vaporizing wall 4 will be vaporized by the heat of combustion taking place within or adjacent the pot. The area or zone of admission of the liquid fuel is shown as adjacent 45 the top of the pot, and thus at the hottest part of the pot. Thus the rate of vaporization will be high when the burner is burning at the high fire stage. However, under normal conditions the liquid fuel will have flowed a perceptible distance 50 down the wall 4 before substantial vaporization takes place. Thus the fuel is vaporized in the zone of admission of primary air. The result is the formation of a preliminary and partly combustible mixture which rises in the pot and which 55 is completed, as a fully combustible mixture, when

it reaches the level of the secondary air inlets 19. Combustion takes place at or above the level of the secondary air inlets 19 and the flame and products of combustion pass into the interior of the heater 1.

We claim:

1. In a pot type liquid fuel burner, a vertical burner pot having a closed bottom and an apertured top wall, a wall structure joining them, having a generally upright, imperforate fuel-vaporizing panel, and a perforate air-admission portion having primary air inlet apertures located at various levels in, and distributed substantially from side to side of, the perforate portion, adapted to direct jets of primary air toward the vaporizing panel, said portion also having a horizontally disposed row of secondary air inlet apertures located below the top wall and above the primary air inlet apertures, means for supplying liquid fuel to the inner surface of the panel below the secondary air inlet apertures and above the primary air inlet apertures, whereby it may flow freely by gravity down the panel to and through the area within which the primary air inlet apertures direct their air jets toward the vaporizing panel.

2. In a pot type liquid fuel burner, a vertical burner pot having a closed bottom and an apertured top wall, a wall structure joining them, having a generally upright, imperforate fuel-vaporizing panel, and a perforate air-admission portion having primary air inlet apertures located at various levels in, and distributed substantially from side to side of, the perforate portion, adapted to direct jets of primary air toward the vaporizing panel, said portion also having a horizontally disposed row of secondary air inlet apertures located below the top wall and above the primary air inlet apertures, means for supplying liquid fuel to the inner surface of the panel below the secondary air inlet apertures and above the primary air inlet apertures, whereby it may flow freely by gravity down the panel to and through the area within which the primary air inlet apertures direct their air jets toward the vaporizing panel, the vaporizing panel being slightly inclined to the vertical from the upper portion inwardly toward the lower portion of the pot.

3. In a pot type liquid fuel burner, a vertical burner pot having a closed bottom and an aper-

tured top wall, a wall structure joining them, having a generally upright, imperforate fuel-vaporizing panel, and a perforate air-admission portion having primary air inlet apertures located at various levels in, and distributed substantially from side to side of, the perforate portion, adapted to direct jets of primary air toward the vaporizing panel, said portion also having a horizontally disposed row of secondary air inlet apertures located below the top wall and above the primary air inlet apertures, means for supplying liquid fuel to the inner surface of the panel below the secondary air inlet apertures and above the primary air inlet apertures, whereby it may flow freely by gravity down the panel to and through the area within which the primary air inlet apertures direct their air jets toward the vaporizing panel, the vaporizing panel being generally planar and the perforate air-admission portion of the wall structure being generally curved.
